MEANS FOR FLOWING WELLS

Samuel Allen Guiberson, III, Dallas, Tex., assignor to The Guiberson Corporation, Dallas, Tex., a corporation of Delaware

Application September 28, 1936, Serial No. 102,863

11 Claims. (Cl. 103—233)

This invention relates to new and useful improvements in means for flowing wells.

One object of the invention is to provide an improved system of flowing wells by means of an auxiliary lifting fluid.

Another object of the invention is to provide an improved system of flowing wells, which is particularly adapted for use in wells which are alternately producing for a comparatively short period each day, being shut down the remainder thereof; said system serving to conserve the lifting fluid by trapping the same in the well casing, whereby it is immediately available when production is again started after a shut down; the conservation of the lifting fluid resulting in a great saving, especially in wells having a low standing liquid level.

An important object of the invention is to provide an improved system of flowing wells which consists in, packing off the well tubing from the well casing at substantially the standing well liquid level in said casing, introducing a lifting fluid into the casing below the packer, and controlling the introduction of the lifting fluid by the pressure of the fluid in the casing above the packing medium.

A further object of the invention is to provide an improved system of flowing wells wherein the well tubing is packed off from the well casing at two spaced points, and a lifting fluid is introduced into the well casing between the packing mediums, whereby the well liquid in this space is lifted through the well tubing; the lower packing medium preventing the pressure of the lifting fluid from contacting the producing sand, while the other packing medium traps the lifting fluid in the casing above the same when the pressure of the lifting fluid above the upper packing medium falls below a predetermined point.

Still another object of the invention is to provide improved means for flowing wells including a packing medium at substantially the liquid level in the well casing, means for introducing the lifting fluid into the well casing below said medium, and a pressure valve actuated by the pressure of the lifting fluid for controlling the introduction of the lifting fluid, whereby when the pressure of the lifting fluid falls to a predetermined point, the valve closes to trap the lifting fluid within the casing above said packing medium; the valve remaining closed until the pressure of the lifting fluid exceeds a predetermined point, thereby conserving the fluid until the next operation.

A still further object of the invention is to provide an improved flow device including a lower packing assembly and an upper packing assembly, with a plurality of flow devices mounted therebetween, whereby the well liquid entering the space between the packers is lifted to the surface by means of an auxiliary fluid and the flow devices.

A construction designed to carry out the invention will be hereinafter described, together with other features of the invention.

The invention will be more readily understood from a reading of the following specification and by reference to the accompanying drawings, in which an example of the invention is shown, and wherein:

Figure 1 is a view, partly in elevation and partly in section, and showing the upper portion of a well flowing apparatus, constructed in accordance with the invention.

Figure 2 is a view, partly in elevation and partly in section, and being a continuation of the parts shown in Figure 1.

Figure 3 is an enlarged view, partly in elevation and partly in section showing the upper packer assembly.

Figure 4 is a continuation of Figure 3 and showing the pressure valve structure.

Figure 4a is an enlarged detail view showing the pressure valve structure.

Figure 5 is a continuation of Figure 4 showing the lowermost end of the device.

Figure 6 is an enlarged view, partly in elevation and partly in section, of the pressure valve structure and the upper end of the lower packing assembly.

Figure 7 is a continuation of Figure 6.

Figure 8 is a horizontal, cross-sectional view taken on the line 8—8 of Figure 3.

Figure 9 is a horizontal, cross-sectional view taken on the line 9—9 of Figure 6.

Figure 10 is a horizontal, cross-sectional view, taken on the line 10—10 of Figure 6.

Figure 11 is a horizontal, cross-sectional view, taken on the line 11—11 of Figure 6, and

Figure 12 is a vertical, sectional view of one of the flow valves.

In the drawings, the numeral 10 designates the usual well casing which extends downwardly to the lower end of the well hole and which has a casing head 11 mounted on its upper end at a point above the ground level. Extending downwardly through the casing head and well casing is the usual well tubing 12. It is noted that the well tubing is suitably supported axially within

- the casing head in any desired manner. An inlet pipe 13 extends radially into one side of the casing head 11 and this pipe has its other end connected with a suitable lifting fluid supply (not shown), such as gas or air. A manually operated control valve 14 may be connected in the line 13. All of these parts are of the usual construction and form no part of the present invention, and are, therefore, subject to variation.
- 10 In carrying out the invention, an upper packing assembly A is connected in the tubing string 12. This packing assembly is preferably located at approximately the standing liquid level in the well casing, although it is to be noted that such location is not essential. Below the upper packing assembly A, a plurality of flow valves B are connected in the tubing string and these valves may vary in number according to the depth of the well. Suspended from the lower end of the 15 well tubing and below the flow valves B is a lower packing assembly C which, when the apparatus is within the well casing, is located near the bottom of the well. Thus, it will be seen that broadly the apparatus comprises a pair of packing assemblies which are spaced from each other and are connected in the tubing string. Between the packing assemblies, a plurality of flow valves B, of any desired construction, are connected in said tubing.
- 20 30 Any desired type of packing assembly may be employed, but I prefer to construct the upper packing assembly A as is clearly shown in Figure 3. This type of packing assembly includes a tubular mandrel 15 having a collar 16 threaded 25 on its upper end. The upper end of the collar 16 is internally threaded to receive the well tubing 12, whereby the mandrel is connected to said tubing. The collar is provided with an annular bevelled valve 17 at its lower end and this valve 35 is arranged to engage an annular seat 18 formed on the upper end of a sleeve 19 which is slidably mounted on the mandrel 15. A coil spring 20a exerts its tension to hold the valve 17 off the seat.
- 40 45 An elastic packing element 20 has its upper end confined within the lower end of the sleeve 19, while its lower end is mounted within an annular retaining member 21 which is also slidable on said mandrel. It is noted that the upper end of the retaining member 21 is spaced 50 from the lower end of the sleeve 19. A second annular elastic packing element 22 is confined between the lower end of the retaining member 21 and a collar 23 which is also slidable on the mandrel 15. The collar 23 normally rests on the upper end of a sleeve 24 which surrounds the mandrel 15. The sleeve is provided with an enlarged bore 24', and a recovery ring 25, welded to the outer surface of the mandrel 15 is located 55 within this enlarged bore 24'. It will be obvious by observing Figure 3 that normally the sleeve 24 is suspended on the ring 25 which is fastened on the outer periphery of the mandrel 15.
- 60 The lower end of the sleeve 24 is made integral 65 with a slip head 26 which head is provided with a plurality of inclined faces 27, whereby gripping slips 28 may be slid vertically on said faces. It is noted that each face is provided with a vertical dove-tail 27' which engages grooves 28' in the rear side of each slip, whereby said slips are held 70 on the faces.
- 75 The lower ends of the slips 28 are pivotally connected to the upper ends of links 29, which links have their lower ends pivoted to a ring 30 which is slidable on the mandrel 15. The ring

normally rests on a supporting collar 31 which is welded or otherwise secured to the mandrel. The ring 30 also engages the upper end of an enlarged sleeve 32 which encircles the mandrel 15 and collar 31. This sleeve has a greater diameter than the diameter of the mandrel or collar and has no connection therewith. The sleeve 32 has the upper end of flat friction springs 33 secured thereto and the lower end of the springs are fastened to a collar 34 which surrounds the 10 mandrel. It is noted that the springs 33 are bowed so that their outer surface is in frictional contact with the wall of the well casing 10. The collar 34 is provided with a hook 35 which normally engages a radially extending pin 36 which 15 is secured to the mandrel 15. When the hook is engaging the pin as is shown in Figure 4, it will be obvious that the collar 34 is fastened to the mandrel 15 so that it moves therewith. When the mandrel is rotated to disengage the pins 36 20 from said hook, it will be obvious that the mandrel may slide with relation to the friction springs 33, collar 34 and sleeve 32 secured to said spring.

The lower end of the mandrel 15 is threaded, whereby the upper end of a pressure valve housing 37 may be fastened thereto. The lower end of the valve housing is provided with an internally screw-threaded axial bore 38, whereby the well tubing 12 may be screwed therein. The construction of the pressure valve housing 37 is 25 clearly shown in Figures 4, 4a and 6, and this housing has a general cylindrical shape, being provided with an extension 39 at one side thereof. This extension is formed with a vertical bore 40 which extends upwardly from the lower end 30 thereof to a radial cross passage 41 located near the upper end of the extension 39. A port 42 extends from the outer surface of the extension 39 and communicates with the upper portion of the vertical bore 40, said port being positioned 40 below the passage 41 in a horizontal plane. A valve seat 43 is formed at the intersection of the port 42 with the vertical bore 40, and this seat is arranged to be engaged by a valve assembly 44, which valve is slidable in the bore 40. As 45 clearly shown in Figures 4, 4a and 6, the lower end of the bore 40 is internally threaded and enlarged at 40', whereby an internal annular shoulder is formed. The valve assembly 44 includes a valve pin 41' having a tapered upper end for engaging the seat 43. The pin is shorter in length than the bore and an annular elastic packing sleeve 42' is located in the lower end of 50 said bore. The packing sleeve is closed at its upper end and has an external shoulder or flange 55 at its lower end, which shoulder is arranged to seat against the internal shoulder between the bore 40 and enlarged portion 40'. The sleeve is held in position by a ring 43' threaded into the lower enlarged portion 40'.

For holding the valve pin 42' in its normally seated position, an elongate headed shank 45 extends through the packing sleeve and has an integral stud at its upper end. The stud passes through the closed upper end of the sleeve and is threaded into the lower end of the valve pin, whereby the pin is carried thereby. The shank has a sliding fit within the sleeve and has its intermediate portion reduced at 45'. A coiled spring 46 is confined within the lower portion 40' of the bore and has its upper end engaging the head of the shank 45, while its lower end engages an adjusting nut 46' threaded within the bore 40'. It is obvious that the spring exerts its pressure to hold the valve pin 41' in engagement with 70 75

its seat, and by moving the nut within the bore 40', the tension of said spring may be varied, whereby a greater or lesser pressure against the pin is necessary to unseat the same. The extreme lower end of the bore 40' may be closed by a suitable plug 47'.

When the pin is seated no communication between the interior of the casing and the radial passage 41 is possible. For actuating the valve 44 to permit a communication between the passage 41 in the valve housing 37, and the interior of the well casing 10 at a point below the upper packing assembly A, an elongate tube 47 has its lower end threaded into a vertical port 48 in the valve housing (Figure 6). The port 48 has a direct communication with the inner end of the radial passage 41. The tube 47 extends upwardly from the valve housing 37, through the tubular mandrel 15 and upwardly to the collar 16 at the upper end of said mandrel. The upper end of the tube 47 is bent outwardly and extends through an opening 49 in the side wall of the collar 16 and the outer end of this tube is opened to the interior of the well casing 10 at a point above the upper packing assembly A. It will be obvious that when gas or other fluid is introduced into the casing above the upper packing assembly A, and said packing assembly is in its set or packed off position, such gas or other fluid may pass downwardly through the tube 47 into the cross passage 41 in the valve housing 37. If the pressure of this gas or other fluid is sufficient to overcome the tension of the spring 46, said gas will unseat the valve pin 41' which will open the port 42, whereby the gas may escape from the passage 41 into the interior of the well casing 10 below the upper packing assembly A. Therefore, it is obvious that the vertical tube 47 provides a by-pass around the packing assembly A when said assembly is set or packed off. The valve 44 is a pressure valve and may be adjusted so that a predetermined pressure must be present in the passage 41, tube 47 and space in the well casing 10 above the packing assembly, before said valve is unseated to permit the escape of such gas into the well casing below said assembly.

The tubing 12 extends downwardly from the valve housing 37 and has a plurality of the flow valves B connected therein. The particular type of flow valve which is employed is not essential to the invention and, therefore, any suitable type of valve may be employed. The details of the particular flow valve employed are clearly shown in Figure 12. Each valve comprises a casing 50 which is connected in the tubing 12. A spring controlled ball valve 51 is arranged to engage a seat 52 adjacent the inlet opening 53, whereby a predetermined pressure must be present in the well casing outside the valve B before the ball 51 is unseated to permit the well liquid standing within the well casing to flow into the tubing 12.

The lower section of the tubing string is formed with an annular flange or ring 54 (Figures 4 and 6). A perforated sleeve 55 extends downwardly from the tubing and is provided with an internal annular shoulder 56 which engages on the flange or ring 54, whereby the sleeve is suspended from the lower end of the tubing string. The lower end of the sleeve 55 is connected by a coupling collar 57 with the upper end of the valve member 58 of the lower packing assembly C. A coil spring 59 is confined within the perforated sleeve 55 and has its upper end engaging the underside of the flange 54 on the lower end of the tubing 12, while its lower end bears

against the upper end of the valve member 58 of the lower packing assembly C. This spring, therefore, constantly exerts its pressure to hold the annular shoulder 56 of the sleeve 55 in contact with the flange 54 of the tubing 12.

The lower packing assembly is constructed substantially the same as the upper packing assembly except that its upper valve member 58 is provided with an axial valve seat 60. This seat is suitably mounted within a valve cage 61 and a ball 62 arranged to engage said seat is confined within the cage. The upper end of the valve member 58 is, of course, provided with an axial bore 58' communicating with the seat 60.

The valve member 58 is carried by the mandrel 15' of the lower packing assembly. An enlarged sleeve 19' having a valve seat 18' at its upper end is slidable on the upper portion of the mandrel 15'. A spring 20' surrounding the mandrel within the bore of the sleeve 19' engages the underside of the valve member 58. A pair of annular elastic packing elements 20' and 22' surround the mandrel 15' being held thereon by the lower end of the sleeve 19', a retaining member 21', and a lower collar 23'. It is pointed out that the various parts of the lower packing assembly are similar to the parts of the upper packing assembly A.

The collar 23' normally rests on the upper edge of an elongate perforated sleeve 63. This sleeve is provided with an internal annular shoulder 64 which rests on a recovery ring 65 which is welded, or otherwise secured, to the outer periphery of the mandrel 15'. The perforated sleeve 63 has a greater inner diameter 35 than the outside diameter of the mandrel and also the lower end of this sleeve extends some distance below the lower end of the mandrel. The lower end of the sleeve 63 is formed with an annular flange 66, which flange is arranged 40 to rest on the bottom of the hole, when it is desired to set the packer as will be explained.

In operation, the device is lowered into the well casing 10, the lower packing assembly being in its retracted position as shown in Figure 5 and the upper packing assembly A also being in its retracted or normal position as shown in Figure 3. During this lowering operation, the pressure valve 44 within the valve housing 37 just below the upper packing assembly, is in its closed 50 position, being held so by the coil spring 46. As the parts are lowered within the well casing, the flange 66 at the lower end of the perforated sleeve 63 which is at the bottom of the entire apparatus, will strike the bottom of the hole (Figure 55 2) to arrest further downward movement thereof. As the perforated sleeve 63 becomes stationary, the mandrel 15' will be moved downwardly within the perforated sleeve 63, whereby the recovery ring 65 on the mandrel 15' will leave the 60 annular internal shoulder 64 within said sleeve. This downward movement of the mandrel 15' will be caused by the weight of the valve member 58 secured to its upper end as well as by the weight of the tubing string 12. It is noted that 65 the weight of the tubing string 12 is placed upon the mandrel 15 by means of the coil spring 59 which is mounted within the perforated sleeve 55 secured to the upper end of the valve member 58 of the lower packing assembly C.

As the mandrel 15' moves downwardly, it will be obvious that the valve member 58 will be moved downwardly into engagement with the seat 18' of the sleeve 19' surrounding the upper portion of said mandrel. When this occurs, the 75

weight of the tubing string, as transmitted through the coil spring 59 will be exerted against the valve member 58. Since the valve is seated, this weight will be exerted on the sleeve 19' which 5 sleeve is slidable on the mandrel 15', whereby the downward movement of the sleeve with relation to the lowermost collar 23' which is resting on the perforated sleeve 63, will cause the elastic packing element 20' and 22' to be expanded into 10 engagement with the wall of the well casing 10. Thus, it will be seen that the lower packing assembly C is thus moved into its set position, whereby the mandrel 15' is packed off from the well casing 10. An upward flow of fluid through 15 the well casing is thereby prevented.

It is noted that upon the downstroke or lowering of the entire assembly into the well casing 10 and prior to the setting of the lower packer, the valve 58 of the lower packing assembly C is held 20 open by the coil springs 20a'. Also the valve 17 of the upper packing assembly A is held open by its coil spring 20a. At the same time the standing valve 62 located at the upper end of the lower packing assembly C is also unseated by the fluid 25 passing upwardly through the mandrel 15' and tubing as the device is being lowered. Therefore, it will be seen that there is an ample bypass space for the well liquid to flow through the assembly as the same is being lowered into the 30 well, whereby resistance to said lowering is reduced to a minimum.

During the setting of the lower packing assembly C, as above explained, the gripping slips 28 of the upper packing assembly A are held in 35 their retracted position due to the engagement of the hook 35 (Figure 4) with the pin 36 of the mandrel 15. Therefore, it is impossible to set the upper packing assembly while the lower packing assembly is moving into its packing position. 40 After the lower assembly C has been set, the tubing string 12 and mandrel 15 connected therewith is rotated so that the pin 36 is disengaged from the hook 35 carried by the collar 34. When this occurs, further downward movement of the 45 tubing string and mandrel will cause the lower end of the tubing 12 below the flow valves to compress the coil spring 59 within the perforated sleeve 55 located above the lower packing assembly. Therefore, the flange 54 on the lower 50 end of the tubing 12 will leave the annular shoulder 56 (Figure 6) of the perforated sleeve. This downward movement of the tubing will cause the mandrel 15 to move downwardly with relation to the friction springs 33 because said springs engaging the wall of the well casing will hold the 55 collar 34 and sleeve 32 to which they are fastened stationary. As the mandrel moves downwardly through the sleeve 32 (Figure 3) it will be obvious that the slips 28 will be held stationary 60 because they are supported on the sleeve 32.

Continued downward movement of the mandrel 15 will cause the valve 17 at its upper end to overcome the tension of the spring 20a and to engage the seat 18 at the upper end of the 65 sleeve 19. When this occurs the weight of the mandrel and tubing string 12 is transferred to the sleeve 19, packing element and collar 23 (Figure 3). Since the collar 23 is resting on the sleeve 24 which carries the slip heads 26 it will be obvious that the weight of the mandrel 15 and tubing string 12 will cause the head 26 to move downwardly with relation to the slips 28 which are held stationary by the friction springs 33. This movement of the head will, of course, 70 expand the slips 28 into engagement with the

wall of the well casing, whereby further downward movement of the head 26 or collar 23 is arrested.

After the slips have engaged the casing wall, the weight of the mandrel 15 and the tubing 5 string 12 is exerted entirely upon the packing elements 20 and 22 through the sleeve 19, causing distortion of said packing element into engagement with the wall of the well casing. After this upper packing assembly A has been set in this 10 manner, it will be seen that the well casing is packed off from the well tubing at spaced points. The lower packing assembly C is preferably located near the lower end of the well, while the upper packing assembly A is located substantially 15 at the normal standing liquid level in the well casing. Between the two packing assemblies, it is obvious that the pressure valve housing 37 and the flow valves B are located. It is noted that this space will, of course, vary with the particular well and, therefore, the number of flow valves which are employed is subject to variation.

After the assembly has been lowered into the well casing 10, and the two packing assemblies A 25 and C have been set as above described, it will be obvious that the well liquid from the bottom of the well will flow through the perforations in the lowermost sleeve 63 and will enter the interior of the mandrel 15' of the lower packing assembly. 30 This liquid will flow upwardly through said mandrel and will unseat the standing valve 62 at the upper end of said assembly. From this point, the well liquid will escape outwardly through the perforated sleeve 55 which is located above the 35 lower packing assembly and thus, the well liquid will enter the casing between the two packing assemblies. Since the upper packing assembly A is located at substantially the liquid level within the casing, it will be obvious that the entire space 40 between the packers will be filled with well liquid.

When the liquid has reached its normal level the valve 62 will automatically close and the liquid will be trapped. The pressure of this trapped liquid in the casing is neutralized by the 45 pressure in the tubing, and the flow valves B will remain closed, and, therefore, unless an auxiliary pressure is introduced the well will not flow. In order to produce this flow, gas, air, or other lifting fluid is introduced into the upper end of the well casing above the upper packing assembly A, through the inlet pipe 13 (Figure 1). This lifting fluid is, of course, under a given pressure and is forced into the well casing. The lifting fluid 50 will flow downwardly in the well casing and will enter the vertical by-pass tube 47 and will pass downwardly therein around the set packer A. This lifting fluid will enter the cross passage (Figure 6) 41 in the valve housing 37 and the pressure of this fluid will be exerted against the valve pin 41. As soon as the pressure of the lifting fluid reaches a predetermined point, it will unseat the valve pin under tension of the spring 46, whereby the lifting fluid may escape past the valve seat 43 through the port 42 and into the interior of the well casing below the upper packing assembly A. As soon as this lifting fluid under pressure contacts the standing or trapped liquid in this space it will be obvious that the increased pressure will immediately kick off the uppermost flow valve whereby a portion of the well liquid will be forced upwardly through the tubing string 12. As the uppermost flow valve B is 55 actuated and the well liquid to this point has been raised, the next flow valve therebelow will 60

be actuated whereby additional well liquid is raised. The remaining kick-off or flow valves B will then operate in order until substantially the entire space between the two packers empties itself of the well liquid.

The incoming gas or other lifting fluid is then cut off and as soon as the pressure in the well casing above the upper packing assembly A falls below a predetermined point, the spring 46 will immediately close the valve 44 whereby the lifting fluid cannot enter the space between the packing assemblies A and C. Therefore, the lifting fluid which is within the well casing between the upper packing assembly and the top of said casing is thereby trapped therein and cannot escape. As soon as this lifting fluid is cut off, and the pressure below the standing valve 62 exceeds the pressure within the space between the packing assemblies, the well liquid will again unseat the valve 62 and flow into said space. As soon as this space is again filled with well liquid, the lifting fluid is again introduced through the line 13 and the pressure of said fluid within the casing above the upper packing assembly is raised to a predetermined point, the valve 44 is again opened and the lifting fluid introduced into the space between the packers, whereby the kick-off valves B are again operated and the well liquid raised to the surface. The lifting fluid may be introduced through the line 13 and its introduction controlled by a manually operated valve which is opened and closed at intervals. If desired, an intermitter D may be mounted in the line 13 whereby the lifting fluid is introduced at the desired interval.

It is noted that with this arrangement the lifting fluid above the upper packing assembly A must reach a predetermined pressure before it is admitted to the space between the two packers where the well liquid is trapped. After the well liquid has been lifted through the well tubing 12, and the lifting fluid being introduced into the upper end of the well casing is cut off, the pressure of said lifting fluid will immediately drop whereby the valve 44 is closed. As this occurs, the lifting fluid is trapped in the space between the valve 44 and the top of the well casing. This is particularly advantageous because the lifting fluid so trapped is conserved until the next operation when the valve 44 again reopens. It is obvious that when using the device in a well where the standing liquid level is comparatively low there is a large space above the packing assembly A and the top of the well casing and thus, a large amount of gas or other lifting fluid which would be otherwise wasted is trapped within the well casing and is utilized upon the next operation of the device. Attention is called to the fact that only the lifting fluid which enters the space between the packing assemblies A and C while the valve 44 is open, escapes through the well tubing. All other gas which fills the space between the upper packing assembly A and the casting head 11 is conserved and, therefore, waste of the lifting fluid is reduced to a minimum.

When it is desired to remove the device from the well casing, it is only necessary to lift the well tubing 12 upwardly. This causes an upward movement of the mandrel 15 of the upper packing assembly and causes the recovery ring 25 welded thereon (Figure 3) to lift the sleeve 24 and slip heads 26, whereby the slips 28 are retracted. When the weight of the tubing string and mandrel 15 is taken off the valve 17 at the upper end of the packing assembly A, the coil

spring will immediately return the valve to its unseated position. Further upward movement of the tubing 12 and mandrel 15 will raise the entire upper packing assembly so that the pin 36 on the mandrel (Figure 4) will strike the underside of the collar 34 to which the friction springs 33 are attached. Rotation of the mandrel and tubing string will cause the pin 36 to again ride into the hook 35 on said collar whereby the friction springs are again fastened to the mandrel. Continued upward movement of the tubing string will cause the flange 54 at its lower end to rise upwardly within the perforated sleeve 55 until said collar engages the internal annular shoulder 56 at the upper end of said sleeve. From this point on, it will be obvious that the collar engaging said shoulder will serve to raise the valve 58 of the lower packing assembly C together with the mandrel 15 thereof. The recovery ring 65 on said mandrel will strike the internal shoulder 64 of the lower perforated sleeve 63 and thus, the entire assembly will be raised.

It is pointed out that the lower packing assembly C serves to prevent the pressure of the lifting fluid which is introduced into the space between the two packers, when said packers are set, from contacting the oil sand at the bottom of the well. This is true because when the lifting fluid is introduced into this space, the pressure thereof will immediately seat the standing valve 62 if said valve has not already been seated. It is pointed out, however, that the lower packing assembly C could be eliminated and the operation of the flow valves B and upper packing assembly A would be exactly the same. The only difference would be that the oil producing sands at the bottom of the well would be subjected to the pressure of the lifting fluid which is introduced below the upper packing assembly A. It is again pointed out that although I have shown a particular type of packing assembly, the invention is not to be limited to the particular type shown. Also the particular type of flow valve B is subject to variation as any type suitable for the purpose and known as a stage lift kick-off valve may be employed.

What I claim and desire to secure by Letters Patent, is:

1. A well flowing device including a tubing string, a packing assembly adapted to be connected to the lower end of the tubing string, a second packing assembly connected in the tubing string and spaced above the first assembly, means for setting said assemblies in the well whereby a packed off space is provided therebetween, said tubing string being provided with apertures to permit the well liquid which flows through the tubing string through the lower packing assembly to enter said space, means for introducing a pressure lifting fluid into said space and a series of stage valves between the packers to permit the pressure lifting fluid to enter the tubing to raise the well liquid to the surface in stages through the tubing, and means for controlling the introduction of the lifting fluid by the pressure thereof.

2. A well flowing device including, a tubing string, a packing assembly adapted to be connected to the lower end of the tubing string, a second packing assembly connected in the tubing string and spaced above the first assembly, means for setting said assemblies in the well whereby a packed off space is provided therebetween, said tubing string being provided with apertures to permit the well liquid which flows through the tubing string through the lower packing assembly to enter said space, means for introducing a

- lifting fluid under pressure into the well casing above the upper packing assembly, a by-pass extending through said assembly for permitting the introduction of the fluid to the space between the packing assemblies, and a series of stage valves between the packers to permit the pressure lifting fluid to enter the tubing whereby the well liquid therein is raised to the surface in stages through the tubing.
5. In combination with a well casing, a tubing string within the casing, an upper and lower packer engaging the casing and tubing string at spaced points forming a chamber, the tubing string being provided with openings above the lowermost packer whereby fluid passing upwardly through said tubing string may flow into said chamber, a series of stage valves between said packers to admit pressure fluid into the tubing and means to introduce a pressure lifting fluid into said chamber, said means including a one way valve, said valve and packers preventing the egress of said lifting fluid except through said stage valves.
10. 3. In combination with a well casing, a tubing string within the casing, an upper and lower packer engaging the casing and tubing string at spaced points forming a chamber, the tubing string being provided with openings above the lowermost packer whereby fluid passing upwardly through said tubing string may flow into said chamber, a series of stage valves between said packers to admit pressure fluid into the tubing and means to introduce a pressure lifting fluid into said chamber, said means including a one way valve, said valve and packers preventing the egress of said lifting fluid except through said stage valves.
15. 4. In combination with a well tubing and casing, a packer packing off the space between the tubing and the casing, a pressure controlled valve through which an auxiliary lifting fluid may be introduced into the casing at a point below the packer and a plurality of stage valves below the packer adapted to be successively opened by the action of the auxiliary lifting fluid so that the liquid below the packer is admitted into the tubing and is lifted to the surface through the tubing in stages.
20. 5. In combination with a well tubing and casing, a packer packing off the space between the tubing and the casing and positioned at substantially the standing level of the oil in the well casing, a pressure controlled valve through which an auxiliary lifting fluid may be introduced into the casing at a point below the packer and a plurality of stage valves below the packer adapted to be successively opened by the action of the auxiliary lifting fluid so that the liquid below the packer is admitted into the tubing and is lifted to the surface through the tubing in stages.
25. 6. In combination with a well tubing and casing, a packer packing off the space between the tubing and the casing, means whereby an auxiliary lifting fluid is introduced under pressure into the casing above the packer, means including a pressure valve whereby the auxiliary lifting fluid is conducted around said packer and to a point below the same, and a plurality of valves below the packer whereby the liquid below the packer is admitted into the tubing at a plurality of spaced points and is lifted to the surface in stages.
30. 7. In combination with a well tubing and casing, a packer packing off the space between the tubing and the casing and positioned at substantially the standing level of the oil in the well casing, a by-pass extending from a source of compressed gas above the packer to a point below the same, a pressure valve normally closing said by-pass but adapted to be opened when the pressure of the gas exceeds a predetermined amount, and a plurality of stage valves below the packer adapted to be successively opened by the action of the auxiliary lifting fluid so that the liquid below the packer is admitted into the tubing and is lifted to the surface through the tubing in stages.
35. 8. In combination with a well tubing and casing, a packer packing off the space between the tubing and the casing and positioned at substantially the standing level of the oil in the well casing, a by-pass extending from a source of compressed gas above the packer to a point below the same, a one way valve in said by-pass so that the compressed gas may flow to a point below the packer into a space below the packer and a return flow thereof prevented, and a plurality of stage valves below the packer adapted to be successively opened by the action of the auxiliary lifting fluid so that the liquid below the packer is admitted into the tubing and is lifted to the surface through the tubing in stages.
40. 9. In combination with a well tubing and casing, a packer packing off the space between the tubing and the casing, a pressure controlled valve through which an auxiliary lifting fluid may be introduced into the casing at a point below the packer, a plurality of stage valves below the packer adapted to be successively opened by the action of the auxiliary lifting fluid so that the liquid below the packer is admitted into the tubing and is lifted to the surface through the tubing in stages, and a second packer positioned beneath the lowermost stage valve and acting as a means to prevent the pressure below the upper packer from being exerted on the bottom of the well.
45. 10. In combination with a well tubing and casing, a packer packing off the space between the tubing and the casing and positioned at substantially the standing level of the oil in the well casing, a pressure controlled valve through which an auxiliary lifting fluid may be introduced into the casing at a point below the packer, a plurality of stage valves below the packer adapted to be successively opened by the action of the auxiliary lifting fluid so that the liquid below the packer is admitted into the tubing and is lifted to the surface through the tubing in stages, and a second packer positioned beneath the lowermost stage valve and acting as a means to prevent the pressure below the upper packer from being exerted on the bottom of the well.
50. 11. In combination with a well tubing and casing, a packer between the tubing and casing at substantially the normal standing level of the well liquid, a second packer placed a substantial distance below the first packer, a plurality of stage valves in the tubing between the packers, means to introduce an auxiliary lifting fluid between said packers, a one way pressure valve in said means, said pressure valve and packers serving as a means to prevent the escape of the auxiliary lifting fluid except through said stage valves.
